UNITED STATES PATENT OFFICE.

EMILE WILKENS, OF WINFIELD, NEW YORK.

MEANS FOR CURLING HAIR.

Application filed May 19, 1925. Serial No. 31,256.

To all whom it may concern:

Be it known that I, EMILE WILKENS, a subject of the German Republic, having declared my intentions of becoming a citizen of the United States, residing at Winfield, county of Queens, and State of New York, have invented certain new and useful Means for Curling Hair, of which the following is a specification sufficient to enable those skilled in the art to which the invention appertains to utilize the same.

The object of my invention is to facilitate and render more uniform the curling of human hair in situ on the head of the person to be treated, as for instance in the formation of curls or permanent waves, so called, by manipulative mechanical winding means in contra-distinction to the method of hand manipulation exclusively, as heretofore resorted to. To this end the invention consists essentially in the specific combination, construction and arrangement of parts and appurtenances described and claimed herein, distinctive features being the hair strand clamping and winding means, and the means whereby the device automatically adapts itself to the requirements of hair of various degrees of coarseness or fineness, and whereby other incidental advantages are attained, all as hereinafter fully set forth.

In the accompanying drawings, I illustrate a practical embodiment of the essential features of my invention in a hair manipulative device of the character designated, although I do not limit myself to the identical form and construction of parts shown by way of exemplification, since changes may be made in minor details, and equivalent mechanical expedients resorted to, with like results, and without departing from the spirit and intent of my invention in this respect.

With this understanding:

Fig. 1, represents what may be called a front elevation of my hair curling device, closed, with the hair wind spindle positioned therein;

Fig. 2, is an elevation taken at right angles to Fig. 1;

Fig. 3, is a sectional elevation with the closure plate in open position;

Fig. 4, is a transverse sectional elevation taken upon plane of line 4—4, Fig. 3;

Fig. 5, is a transverse section taken upon plane of line 5—5, Fig. 2;

Fig. 6, is a view like unto Fig. 1, showing a strand of hair under treatment;

Fig. 7, is a similar view showing the wind of the strand of hair nearly completed;

Fig. 8, is a detail view of the hair-wind spindle;

Fig. 9, is a transverse section taken upon plane of line 9—9, Fig. 7;

Fig. 10, is a transverse section taken upon plane of line 10—10, Fig. 2;

Fig. 11, is a detail view of the ratchet post;

Fig. 12, is an edge elevation of the pawl plate;

Fig. 13, is a view of the upper side of said pawl plate;

Fig. 14, is a transverse section taken upon plane of line 14—14, Fig. 1.

The main section of my hair curling device consists of a basic tubular member B, the lower portion B', of which is semi-cylindrical, and provided with a corresponding semi-cylindrical closure section or door C, particularly connected by the hinge a, to said extension B', of the base tube B, and said closure section C, being formed with an integral upper manipulative extension c, hinged to the tubular main member B, as by the supplementary hinges a', a'', the free extremity of said extension c, being formed with a laterally protuberant finger bearing c'.

b, is a clasp spring rigidly attached to the basic tube B, and extending in part around and contacting with the closure section C, its function being to tend constantly to hold said closure section C, in alignment with the tube B, while admitting of the forcible opening of said closure section C, by means of the manipulative extension c, thereof, as indicated more particularly in Fig. 3 of the drawings.

b', b'', are elastic resilient spring jaws or loops rigidly attached to the tube B, (see particularly Fig. 9) and adapted to hold and support the otherwise free end of a strand of hair, as indicated in Fig. 6, of the drawings.

The lower semi-cylindrical extension B', of the tube B, is formed with a rigid lateral flange b'', provided with comb teeth b'', and with an elastic resilient rubber cushion b''. In like manner the lower portion of the closure section C, is formed with a rigid lateral flange extension c'', having an elastic

resilient rubber cushion c^3 , which is opposed, when the parts are in closed relationship, to the cushion b^4 , on the tube extension b^2 , as shown more particularly in Fig. 10, of the 5 drawings.

Fitting in and rigidly attached to the upper end of the tube B , is a cylindrical plug D , formed with a screw-threaded stud d , for engagement with a binding nut d' .
10 In conjunction with a bearing washer d^2 , the nut d' , holds the rotative head H , in position on the upper end of the basic tube B . The head H , is hollow, and closed on its under side by means of a plate h , rigidly
15 attached, and which plate h , I designate as the pawl plate, since it has mounted on its inner surface the pawls p , p , which engage with a ratchet wheel r , rigidly affixed to the screw stud d , of the plug D , reference being
20 had in this connection more particularly to Figs. 3 and 4, of the drawings.

The head H , is preferably provided with radial handles h' , h' , to facilitate manipulation thereof, the function of the head H ,
25 thus equipped being the rotation by hand in one direction of the tube B , and its appurtenances as and for the purpose hereinafter set forth.

b^x , is a spring bearing mounted externally
30 on the semi-cylindrical extension B' , of the basic tube B , and protuberant inward through an aperture formed for the purpose in said extension B' ; and c^x , is a corresponding and opposed spring bearing
35 mounted on the closure C , and protuberant through an aperture formed therein for the purpose, the function of these two spring bearings b^x , and c^x , being to frictionally contact with the periphery of the hair-wind
40 spindle S , which they centralize and support laterally as related to the tube B , while admitting of the rotation of the tube around said spindle S , during the hair winding operation, as will be understood by reference
45 more particularly to Figs. 5 and 9, of the drawings.

The said hair-wind spindle S , is independent of the tubing B , B' , C , within which it fits without contact therewith aside from
50 its contact with the aforesaid lateral bearing springs b^x , c^x , its upper extremity s , being convex to facilitate its insertion therebetween. As will be seen by reference more particularly to Fig. 8, of the drawings, the hair-wind spindle S is essentially a straight cylindrical rod formed at its lower end with a laterally extending loop s' , which functions not only as a handle to hold the spindle
55 manually against rotation, but also as an eye through which a strand of hair x , may be passed, as indicated more particularly in Figs. 6 and 7, of the drawings.

In the use of the hair-curling means herein shown and described, a strand of hair
60 x , is first threaded through the loop s' , of

the wind-spindle S , and a preliminary wind of the strand effected around the adjacent portion of said spindle S . The closure section C , is then opened by means of its manipulative extension c , more or less, as
70 indicated in Fig. 3, of the drawings, the spindle S , inserted in the tube B , and its extension B' , the closure section C , released to complete the envelopment of the wind-spindle S , and the strand of hair x , passed through the comb b^3 , and into and through the spring loops b' , b' , which clasp the otherwise free portion of said strand of hair x , as indicated in Fig. 6, with an elastic
75 resilient pressure, sufficient to sustain the same during the winding operation until near the completion thereof, when said outer portion of the strand of hair x , is drawn taut, the proximate completion of the
80 winding operation withdrawing the hair from between said spring loops b' , b' , and into the relative position indicated in Fig. 7, of the drawings. At this stage of the wind operation a binding strip for the extremity of the hair strand is inserted
85 through the slot c^4 , in the closure section C , to afford means for securing together the otherwise loose ends of hair, when the said closure section may be re-opened to facilitate the removal of wind-spindle and the
90 convolutions of hair thereon.

During the wind operation the spindle S , is held against rotation by means of the loop s' , either by the fingers of the operator, or through the medium of a clamping implement adapted to the purpose, the rotation of the tubular encasement B , B' , C , around said wind-spindle being effected by means of the head H , or equivalent mechanical expedient, said head H , functioning
100 as a handle in this respect for the tubing. The head H , provided with the internal pawl and ratchet arrangement shown, although not indispensable, is preferable as a handle for the purpose designated because by its use, the operation of turning the tubing, etc., around the wind-spindle S , may be expedited, although I do not limit myself to this form and construction of
105 handle.

The rubber cushions b^4 , c^3 , tend to hold the strand of hair x , taut, and to compensate for variations in fineness or coarseness of hair to be treated, while the comb teeth
110 b^3 , insure the alignment and parallelism of the hairs of the strand as wound upon the spindle S .

By the use of my hair curling appliance desired results are quickly attained with facility, and in a more satisfactory manner as compared with direct finger manipulation as heretofore—the saving in time and labor, and the uniformity and perfection of curl attained involving important advantages in art.

130

What I claim as my invention and desire to secure by Letters Patent, is:—

1. Hair curling means of the character designated, comprising a wind-spindle, and a rotatable tubular enclosure therefor, formed with lateral comb teeth, substantially as and for the purpose set forth. 5
2. Hair curling means of the character designated, comprising a wind-spindle, and a rotatable tubular enclosure therefor, formed with lateral comb teeth, and with elastic resilient loop means for holding a strand of hair, substantially as and for the purpose set forth. 10
3. Hair curling means of the character designated, comprising a wind-spindle, and a rotatable tubular enclosure therefor, formed with lateral comb teeth, and with a hinged closure section, substantially as and for the purpose set forth. 15
4. Hair curling means of the character designated, comprising a wind-spindle, and a rotatable tubular enclosure therefor, formed with lateral comb teeth, and with internally positioned rubber cushion means, substantially as and for the purpose set forth. 20
5. Hair curling means of the character designated, comprising a wind-spindle, and a rotatable tubular enclosure therefor, formed with lateral comb teeth, and formed with spring bearings for contact with said wind-spindle, substantially as and for the purpose set forth. 25
6. Hair curling means of the character

designated, comprising a wind-spindle, and a rotatable tubular enclosure therefor, formed with lateral comb teeth, and with a hinged closure section and spring, substantially as and for the purpose set forth. 40

7. Hair curling means of the character designated, comprising a wind-spindle, a rotatable tubular enclosure therefor formed with a closure section, and with lateral comb teeth, substantially as and for the purpose set forth. 45

8. Hair curling means of the character designated, comprising a wind-spindle, a rotatable tubular enclosure therefor formed with a closure section, and with lateral comb teeth, and also formed with rubber cushion means, substantially as and for the purpose set forth. 50

9. Hair curling means of the character designated, comprising a wind-spindle, a rotatable tubular enclosure therefor formed with a spring closure section, and with comb teeth, rubber cushion means, and external elastic resilient hair loop means, substantially as and for the purpose set forth. 55

10. Hair curling means of the character designated, comprising a wind-spindle, a rotatable tubular enclosure therefor formed with a spring closure section, and with comb teeth, rubber cushion means, and external elastic resilient hair loop means, together with lateral bearing springs for contacting with said wind-spindle, substantially as and for the purpose set forth. 60 65

EMILE WILKENS.
